(57) **CLAIM**

The ornamental design for a faucet handle, as shown and described.

DESCRIPTION

FIG. 1 is an isometric view of a faucet handle showing my design;

FIG. 2 is a top plan view of my faucet handle design;

FIG. 3 is a bottom plan view of my faucet handle design;

FIG. 4 is a front elevational view of my faucet handle design;

FIG. 5 is a left side elevational view of my faucet handle design (the right side elevational view is a mirror image of the left side elevational view); and,

FIG. 6 is a rear elevational view of my faucet handle design.

Features illustrated in FIGS. 1-6 using broken lines are shown for illustrative purposes only and form no part of the claimed design.
